DESIGN FOR AN ELECTRICAL WALL OUTLET

Melvin S. Adler, Chicago, Ill.

Application June 28, 1947, Serial No. 139,997

Term of patent 14 years

(Cl. D26—13)

To all whom it may concern:

Be it known that I, Melvin S. Adler, a citizen of the United States of America, residing at 3730 North Southport Avenue, Chicago, Illinois, have invented a new, original, and ornamental Design for Electrical Wall Outlets, of which the following is a specification, reference being had to the accompanying drawing, forming part thereof.

Fig. 1 is a perspective view of an electrical wall outlet with the fuse holder spaced therefrom, showing my new design.

Fig. 2 is a top plan view, and

Fig. 3 is a side view.

Fig. 4 is an end view, and

Fig. 5 is a bottom plan view on a reduced scale.
I claim:

The ornamental design for an electrical wall outlet, as shown.

MELVIN S. ADLER.
